UNITED STATES PATENT OFFICE.

HARRY COMSTOCK, OF FULTON, NEW YORK, ASSIGNOR TO THE HUNTER & COMSTOCK ARMS COMPANY, OF SAME PLACE.

BREECH-LOADING GUN.

SPECIFICATION forming part of Letters Patent No. 409,017, dated August 13, 1889.

Application filed March 9, 1889. Serial No. 302,611. (No model.)

To all whom it may concern:

Be it known that I, HARRY COMSTOCK, a citizen of the United States, residing at Fulton, in the county of Oswego and State of New York, have invented new and useful Improvements in Breech-Loading Guns, of which the following is a specification.

My invention relates to that class of firearms having concealed hammers or strikers, and which are broken or opened at the breech to load and withdraw the empty shells, the cartridges being exploded by rebounding hammers or firing-pins operated by strikers. In the various guns of this type now in use, owing to the want of proper leverage and of a judicious application of power, much difficulty has been experienced in opening the barrels, many opening with such resistance as to require the user to place the gun over the knee and expend considerable force in overcoming the power of the main spring or springs, which must be brought to full tension in order to insure discharge. A highly important feature in this class of mechanism is to reduce the friction of the parts to the minimum and to apply the leverage of the barrels to such advantage and in such manner that the operation of the top lever releasing the barrels will open the breech, without drawing the shells, and cock the strikers without material exertion upon the part of the user. Moreover, in the various types of concealed-hammer guns heretofore in use, the large number of parts required in proportion to the small size of the frame renders it necessary that said parts shall be constructed upon so small a scale and be so compactly arranged that they are necessarily weak, and the great strain concentrated upon them renders it necessary that the operator shall exercise considerable care and caution in handling the piece to prevent fracture.

It is the purpose of my invention to provide a concealed-hammer gun which is cocked by the mere weight of the barrels when they are thrown down to open the breech, and in which the parts shall be so simple and so greatly reduced in number that they may be made of a size and strength sufficient to resist any strain that may be brought upon them. I also propose to provide simple and

novel means for checking the lift of the breech, for actuating the cocking-levers from a point just behind the axis of the pivot-bolt on the frame, for avoiding friction between the cocking-levers and the tangs of the strikers upon which the levers act and between the other parts employed, for locking the triggers when the piece is carried at cock, and for locking the top lever when the breech is opened and releasing it at the proper moment automatically to lock the breech. I also propose to simplify and improve guns of this class and to render them more certain, efficient, and speedy in operation; and to these ends the invention consists in the several novel features of construction and new combinations of parts hereinafter fully set forth, and then definitely pointed out in the claims which follow this specification. 70

Referring to the accompanying drawings, Figure 1 is a side elevation of a gun embodying my invention, with parts of the stock omitted to more clearly exhibit the internal mechanism. Fig. 2 is a similar view showing the barrels dropped to open the breech. Fig. 3 is a plan view of the parts in the position shown in Fig. 2. Fig. 4 is a sectional elevation of the parts shown in Fig. 1. Fig. 5 is a bottom plan view of the breech portions of the barrels removed from the frame. Fig. 6 is a plan view of the frame, the barrels being removed. Fig. 7 is a plan view of the frame inverted. Fig. 8 is a detail perspective of the locking-post and top lever detached. Fig. 9 is a detail perspective of the cocking-levers with the cocking-yoke and its spring. Fig. 10 is a vertical section of the cocking-yoke, showing the shaft and the means for fastening the same in place in the yoke. Fig. 11 is a detail perspective of one of the strikers detached. Fig. 12 is a detail view of one of the strikers with its tripping-plate and spring. Fig. 13 is a detail perspective of one of the trigger-plates and its sear detached. 95

In the said drawings the reference-numeral 1 designates the barrels of a shotgun or other fire-arm, while the numeral 2 denotes the frame. In the fore end of said frame is the pivot-bolt 3, making engagement with a half-round seat 4, formed in the drop-plate 5 of the barrels, which drops between the side

pieces of the centrally-divided frame, positive engagement being insured by the wear-plate 6, which seats upon the half-round fore end of the frame, which is struck upon a curve 5 slightly eccentric to the axis of the pivot-bolt 3. The wear-plate has an arm 7, of usual form, provided with a slot 8 to engage the drop-plate 9 on the barrels, the latter having a cross-slot 10 to receive the tie connecting 10 the wooden stock to the barrels.

The forward portion of the frame 2 is centrally slotted as far as the breech-shoulder 12, and in this slot 2^a, just in rear of the pivot-bolt 3, is arranged a yoke-frame 13, having a 15 pivotal bearing 14 in its upper end, while in the lower broadened end of the side pieces of the yoke are drilled openings which loosely receive a cross-shaft 15, parallel with the bearing 14 and extending through vertical 20 slots 16 in the slotted frame. Upon these extremities are formed pintles or reduced bearings 17. This cross-shaft lies immediately above the flat lower connection of the yoke and is centrally flattened on one side, and in 25 the space so formed a flat steel spring 18 is placed, lying on the base of the yoke and between it and the shaft. This spring prevents longitudinal displacement of the shaft 15, but is readily removed, whereupon the shaft 30 can be withdrawn without effort. One end of the spring may be detachably connected to the frame. The pivotal bearing 14 of the yoke catches a bearing upon a hook 19, formed on the drop-plate 5 of the barrels. It will be 35 noticed that this hook-shaped seat is very near the center of pivotal movement of the barrels when the breech is opened.

Upon the pintles 17 are slipped the ends of the cocking-levers 20, consisting of flat steel 40 strips drilled to receive the pintles and having their filerums upon screws 21, tapped into the sides of the frame. These levers extend rearwardly from these points and curve slightly upward until their extremities lie 45 side tangs 22, projecting rearwardly from the strikers 23. The latter are composed of quadrilateral blocks of metal having flattened shanks 24, in which are cut grooves in which the tangs 22 lie flush, curving outward to 50 bring their ends close to the ends of the cocking-levers, on which are mounted studs 25, which lie upon the upper edges of the tangs 22, and are provided with circular heads 26, engaging the inner surfaces of the tangs 22 55 and preventing disengagement. A friction-collar of hardened steel may surround each of said studs and roll upon the tang of the striker. The strikers are pivoted upon a bolt or pin 27 and impelled by mainspring 28, of 60 suitable construction.

In rear of the drop-plate 5 is formed a depending central lug 29, in the rear edge of which is cut the locking-recess 30, and projecting centrally toward the rear from between the barrels is a lug 31, having a locking-recess 32, the top of the lug being in the line of sight. In the breech-piece 33 is cut a

groove 34, which receives the lug 31, the heavier lug 29 dropping into the rearward end of the slot 2^a of the frame. Lying partly in 70 a central recess in the rear of the breech-piece 33 is a steel post 35, stepped in a bearing below and supported at its upper end in a bearing formed partly in the breech-piece and partly in the rearwardly-projecting top 75 piece 36 of the frame. Projecting above the latter bearing the post receives the rigidly-attached end of the top lever 37, which is laid in a recess 38 cut in the breech-piece and top piece, whereby the surface of said lever is 80 brought flush with the metal surfaces surrounding it. The recess 38 is cut to allow the top lever to swing a short distance to the right, thereby causing a partial rotation of the post 35, by which increased tension is 85 imparted to a strong spring 39, bent upon itself, one end bearing against a pin 40, dropped from the top piece, while the other end is caught by the end of a screw 41, projecting from the post. By the power of this spring 90 the post is turned back after each operation of the top lever. The spring is rigidly connected to the top piece of the frame at the point where it is folded upon itself.

Projecting from the upper part of the post 95 35 is a locking-cam 42, moving in a horizontal slot in the breech-piece, and when in normal position projecting into the central groove 34 of the breech-piece far enough to fully engage the locking-recess 32 in the central lug 31. 100 Upon the lower part of the post 35 is a much heavier and stronger locking-cam 43, which swings in a horizontal slot 44 in the frame, cut some distance below the top of the slotted portion of the latter and above the bottom of 105 the central slot 2^a, into the rear end of which the locking-cam projects far enough to fully engage the locking-recess 30 in the lug 29 when the latter is thrown into the slot 2^a to 110 close the breech. Lying in a seat formed in the rear end of the central groove 34 is a round stop-bolt 45, normally thrown upward by a 115 spring 46. This bolt has a slot 47 running upon a rib in the bolt-seat to limit its upward movement. Normally this bolt, which fills 120 the rear end of the groove 34, would lie in the path of the locking-cam 42 and prevent it from traversing the end of said groove. Thus, 125 as the top lever 37 is thrown to the right and the post 35 rotated, the end of the locking-cam 42, which normally overlies and holds the stop-bolt down, is withdrawn from the groove 34 at the moment the top lever reaches its limit of movement. The bolt thus released rises in the groove 34 and lies in the path of 130 the cam 42, holding it and the post 35 and top lever 37 against the tension of the spring 39. As the barrels are thrown up to close the breech, however, and as the lug 31 thereon enters the groove 34 it strikes the stop-bolt 135 45 and drives it down in its seat. The instant the top of the bolt passes below the locking-cam 42 the post is released and the cam flies against the tang of the lug 31 below the re-

cess 32, and as the latter drops to place both the locking-cams 42 and 43 spring into the locking-recesses with which they respectively engage.

5 The entire operation is, of course, practically instantaneous, and is substantially as follows: In charging the gun, which is handled in the usual manner, the top lever is thrown to the right, rotating the post 35 and withdrawing the locking-cams from their recesses. The breech being thus released, the barrels drop of their own weight, and as the lug 31 rises out of the groove 34 in the breech-piece it is closely followed by the stop-bolt 45, which retains the locking-cams in position to re-engage the recesses in the lugs on the barrels. The fall of the barrels lifts the yoke 13, raising with it the power ends of the cocking-levers, and by reason of the manner in which the power is applied and friction avoided the strikers are cocked by the weight and leverage of the barrels only, the very short space between the pivotal seat on the barrels and the hooked seat for the pivotal bearing of the yoke-frame giving an immense power to the cocking-levers. When shells are introduced, the barrels are thrown up, lifting the cocking-levers off the tangs of the strikers. As the breech sinks to place, the lug 31 drives down the stop-bolt 45, releasing the locking-cam 42, which springs into the locking-recess 32, while the heavier locking-cam 43 enters the locking-recess 30 in the lug 29. The piece is now in condition to be discharged. Upon 35 the central plate 48 of the frame is a pivoted cam-lever 49, which straddles said plate, its ends dropping below the point of pivotal attachment and having surfaces or curves 50, which overhang the upper edges of the tripping-plates 51 of the triggers. Connected to the lever 49 is a link-bar 52, the other end of which is pivotally connected to a plate 53, dropped through a slot 54 in the top piece of the frame and carried by a push-button 55, 45 sliding on the top piece. Retracting this push-button throws the cam-surfaces 50 against the edges of the tripping-plates 51 of the triggers and locks them, so that no discharge is possible until they are released. 50 Any suitable means for maintaining a proper degree of frictional contact between the push-button and its support to render accidental displacement impossible may be employed.

I have not shown any shell-extracting devices in this application, as I may employ any pattern thereof most desirable. The ordinary parts, also, not specifically set forth herein, may be of any preferred form.

It will be noted that by making the cocking-levers of flat steel-plates I am able to obtain great strength and rigidity with very slight thickness of metal, as the entire strain upon these levers is in the direction of their width or greatest dimension. Practically, 65 therefore, I obtain a lever stronger than one having a breadth and thickness each equal to

half the breadth of my flat levers. I thus obtain levers of great strength without in any way increasing the lateral dimensions of the frame and its adjuncts or crowding the parts 70 of the mechanism.

No screws are used in the connecting of the parts, this being all accomplished by pins of the finest Stubbs steel wire.

By my invention I provide a compact, light, 75 strong, and exceedingly simple gun at a low expense, in which the breech may be opened by simply tripping the top lever, without other exertion on the part of the operator. At the same time the shells are withdrawn and 80 the concealed hammers or strikers cocked, the whole being accomplished by the weight of the barrels applied through an exceedingly simple system of levers so arranged that the gravity of the falling barrels is amply sufficient to accomplish these results, in view of the great reduction in friction and the direct and advantageous application of the power, due to the great simplicity and compact arrangement of the parts. 90

It will be seen, also, that the loop carrying the shaft to which the cocking-levers are connected operates as a check to the lift of the breech.

Having thus described my invention, what 95 I claim is—

1. In a concealed-hammer gun, the combination, with a slotted frame, of barrels pivoted thereon and provided with a lug, a loop or yoke engaging the lug and having a shaft 100 extending through slots in the frame, the pivoted cocking-levers connected with and operated by the shaft of the loop or yoke, and strikers arranged adjacent to the rear ends of the cocking-levers and cocked by the latter, 105 substantially as described.

2. In a concealed-hammer gun, the combination, with a slotted frame, of pivoted barrels having a hooked lug, a loop or yoke arranged in the slotted frame engaging the 110 hooked lug and having a shaft at its lower portion extending through slots in the frame, the pivoted cocking-levers pivoted on the frame and connected at their front ends with the shaft of the loop or yoke, and strikers 115 pivoted in the rear part of the frame and having rearwardly-projecting tangs acted on by the rear ends of the cocking-levers to cock the strikers, substantially as described.

3. In a concealed-hammer gun, the combination, with a slotted frame and barrels pivoted thereon and having a lug, of a loop or yoke engaging the lug and having a shaft extending through slots in the frame in rear of the barrel-pivots, the cocking-levers pivoted 120 to the frame and having their front ends connected with the shaft of the loop or yoke and their rear ends provided with lateral studs, and strikers pivoted in the rear part of the frame and having rearwardly-extending tangs 125 on which the studs on the cocking-levers rest, substantially as described.

4. In a concealed-hammer gun, the combination, with a slotted frame and barrels pivoted thereon and having a hook in rear of the barrel-pivot, of a loop or yoke arranged in the frame engaging the hook and having a shaft extending through slots in the frame, the strikers pivoted in the rear part of the frame and having rearward-projecting tangs, and cocking-levers pivoted to the frame, connected 10 at their front ends with the shaft of the loop or yoke, and having studs at their rear ends provided with circular heads overlapping the faces of the striker-tangs, substantially as described.
- 15 5. In a concealed-hammer gun, the combination, with a frame and barrels pivoted thereon and having a hook in rear of the barrel-pivot, of a loop or yoke engaging the hook and having a shaft, the strikers pivoted in 20 the rear part of the frame and having rearward-projecting tangs, and the cocking-levers composed of flat steel plates fulcrumed on the opposite faces of the frame, connected with the shaft of the loop or yoke, and having studs at their rear ends provided with heads overlapping one side of the striker-tangs, while the cocking-levers lie on the opposite side thereof, substantially as described.
- 25 6. In a hammerless gun, the combination, with a spring-actuated post journaled in the rear of the breech-piece and operated by the top lever, of barrels pivoted on the frame and provided with two central lugs, one projecting to the rear and having a locking-recess 30 and the other depending from below and having a similar locking-recess, and a stop-bolt lying in a seat in the rear end of a central groove in the bridge-piece and thrown upward by a spring, the post being provided 35 with a locking-cam normally lying in the rear end of the groove in the breech-piece and having a heavier locking-cam normally lying

in the rear end of the central slot of the frame, whereby, upon closing the breech, the rearwardly-projecting lug on the pivoted barrels enters the central groove in the breech-piece, driving down the stop-bolt, releasing the lug pressing against it, and thereby enabling the spring-actuated post to throw both locking-cams into the locking-recesses of the 45 50 respective lugs on the barrels as the breech sinks to place.

7. In a concealed-hammer gun, the combination, with a slotted frame and barrels pivoted thereon and provided in rear of the pivot with a lug, of a loop or yoke engaging the lug and having a flattened shaft extending through slots in the frame, a flat spring acting at one end upon the flattened part of said shaft and detachably secured to the frame 60 at its other end, cocking-levers fulcrumed on the frame and connected at their front ends with the shaft of the loop or yoke, and strikers pivoted in the rear part of the frame and having rearward-projecting tangs acted on by 65 the rear ends of the cocking-levers, substantially as described.

8. In a hammerless gun, the combination, with the tripping-plates of the triggers, of a cam-lever straddling and pivoted to a plate 70 on the frame between the tripping-plates, said levers having eccentric or cam surfaces overhanging the tripping-plates, and a push-button adjustable on the central top piece of the frame and having a drop-plate lying 75 in a slot in the top piece and connected to the free end of the cam-lever, substantially as described.

In testimony whereof I have affixed my signature in presence of two witnesses.

HARRY COMSTOCK.
